UNITED STATES PATENT OFFICE.

CLARK E. CARTER, OF MONTREAL, QUEBEC, CANADA, ASSIGNOR TO ALADDIN CINEMA CO. INC., OF MALONE, NEW YORK, A CORPORATION OF NEW YORK.

CINEMATOGRAPHIC MACHINE.

1,412,509.

Specification of Letters Patent. Patented Apr. 11, 1922.

Original application filed November 5, 1919, Serial No. 335,953. Divided and this application filed May 10, 1920. Serial No. 380,147.

To all whom it may concern:

Be it known that I, CLARK E. CARTER, a subject of the King of Great Britain, residing at Montreal, Province of Quebec, Canada, have invented certain new and useful Improvements in Cinematographic Machines; and I do hereby declare that the following is a full, clear, and exact description of the invention, such as will enable others skilled in the art to which it appertains to make and use the same.

The present invention relates to cinematographic machines and is the continuation of my application filed November 5, 1919, Serial Number 335,953.

It is the purpose of the present invention to provide a film feeding mechanism for such moving picture machines whereby the film will be drawn through the machine in a more positive and efficient manner without breaking or otherwise injuring the film.

A further object of the invention is to provide an escapement for such film feeding mechanism whereby each picture of the film will be intermittently and quickly advanced to the exposure opening and momentarily retained in this position whereby a much clearer picture will be projected upon the screen.

Other objects of this invention will appear hereinafter and it consists of a motor-driven mechanism which is operatively connected to the film feeding sprockets of the machine, a beater roller operatively connected to such mechanism through an escapement, means for holding the film taut as it passes through the exposure opening and other combination, formation and arrangement of parts as will hereinafter be more particularly described and pointed out in the appended claims.

In the accompanying drawings:

Figure 1, is a detail vertical section through the machine head of the cinematograph apparatus showing the film gate in side elevation;

Figure 2, is a similar detail section showing the film gate in section taken on the line 2-2 of Figure 3;

Figure 3, is a detail section through the machine head taken at right angles to Figure 1 showing the film gate in front elevation;

Figure 4, is an enlarged detail view of the framing device;

Figure 5, is a vertical section taken through the machine head and gear casing on the line 5-5 of Figure 6;

Figure 6, is a vertical section through the gear casing taken on the line 6-6 of Figure 5;

Figure 7, is a vertical section taken on the line 7-7 of Figure 5;

Figure 8, is a detail section view through the gear casing illustrating one position of the escapement; and,

Figure 9, is a similar view looking at the opposite side of the escapement mechanism.

Reference now being had to the drawings wherein like and corresponding parts are designated by like reference characters throughout the several views,

A portion of the machine head of the moving picture machine is represented by the numeral 1 through which is fed the film 2 carrying the pictures. This film is fed from the upper magazine 3, over the upper sprocket wheel 4, through the film gate 5, over the beater roller 6, then by the framing roller 7, over the lower sprocket wheel 8 and then to the film receiving magazine. The rays of light from the lamphouse project through the opening 9 in the machine head, through the film, then through the film gate and then through the lens holder 10. Arranged at one side of the machine head 1 is a casing 11 having arranged therein a suitable driving mechanism for driving the sprocket wheels 4 and 8 and also the beater roller 6 whereby the film will be drawn through the machine.

The upper sprocket 4 is mounted upon a shaft 12, one end of which extends through the casing 11 and is journaled therein. The lower sprocket wheel 8 is carried by the shaft 13 which also has one end extending through the casing 11 and journaled therein. A shaft 14 is mounted in the casing 11 and the bearing 15 carried by the bracket 16 which is suspended within the casing 11. Keyed to this shaft 14 is a pulley-fly wheel 17 over which passes a suitable belt or strap 18, the latter being operatively connected to a motor or other means for rotating the pulley 17 whereby the film feeding mechanism will be propelled. Keyed to the inner end of the shaft

14 is a pinion 19 and this pinion is in constant mesh with the gear wheels 20 and 21 mounted upon the respective sprocket wheel shafts 12 and 13.

5 The beater roller 6 is carried by one end of the arm or bar 22 and the opposite end of this bar 22 is pivotally supported upon a cross shaft 23. A link 24 is pivotally connected to this bar 22 and eccentrically connected as at 25 to the pinion 19 so that as the shaft 14 is rotated the gears 20 and 21 will also be rotated and an oscillating movement will be given to the bar 22 whereby the beater roller will also oscillate through an 10 arcuate slot 26 formed within the casings 1 and 11.

The main driving shaft 14 is provided with a worm gear 27 and meshing therewith is a gear 28 carried by the shutter shaft 29. 20 This shutter shaft 29 is journaled within the casing 11 and carries a shutter 30.

The lower sprocket shaft 13 is provided with a pulley 31 over which passes a suitable spring belt 32 and the latter being provided 25 for propelling the film reel arranged within the lower receiving magazine.

Keyed to this sprocket shaft 13 is an escapement wheel or disk 33. This disk 33 is provided with a plurality of radially extending recesses 34. The beater arm 22 is provided with a laterally extending pin 35 which is adapted to ride upon the outer periphery of the disk 33 and drop within each 30 recess 34 whereby the shaft 13 may momentarily be retained against rotation.

The gear 21 is loosely mounted upon the shaft 13 and is provided with a laterally extending pin 36 which extends through an arcuate slot 37 formed within a disk 38 40 and the latter being keyed to the shaft 13 and arranged adjacent to the gear 21. Secured to one face of this disk 38 as at 39 is a leaf spring 40 and the outer free end of this leaf spring presses against the pin 36 45 so that when the gear 21 is rotated the pin 36 will press against the spring 40 thereby carrying the disk and the shaft 13 with the gear wheel.

From the foregoing it will be apparent 50 that when the shaft 14 is set in motion the gears 20 and 21 will be rotated and the beater arm 22 will also be oscillated. As the gear 20 revolves the upper sprocket wheel 4 is carried therewith and likewise when the gear 55 21 rotates a rotary movement will be transmitted to the shaft 13. As the pinion 19 rotates it will draw the bar 22 upwardly to the position shown in Figure 6 whereby the beater roller will be moved to its uppermost 60 position for engaging the film and upon the downward stroke of the arm the beater roller will draw the film through the film gate. The stroke of the beater is so calculated with the length of the pictures upon the film that 65 upon the downward stroke of the beater

roller one picture will be drawn through the gate. Upon this down stroke of the arm 22 the pin 35 will enter one of the recesses 34 of the escapement disk 33 whereby this disk will be held against rotation and as this disk 70 33 is keyed to the shaft 13, this shaft will be held against rotation, likewise the sprocket wheel 8 thereby momentarily holding a picture within the film-gate. At the same time the gear 21 is still rotating in the direction 75 of the arrow as shown in Figure 9 whereby the tension of the spring 40 will be increased due to the pin 36 pressing thereagainst and the disk 38 being held stationary as it is also keyed to the shaft 13. Upon the upward 80 stroke of the bar 22 the escapement disk 33 will be released and the spring 40 will cause the shaft 13 to turn quickly and again catch up with the gear wheel 21 so that the lower sprocket wheel 8 will be again rotated for 85 drawing that portion of the film which has passed by the beater roller.

In the meanwhile the film while passing through the film gate should be held taut and to so retain the film without breaking or 90 otherwise injuring the same I have provided a film gate as shown. This film gate comprises a main section 41 having an opening 42 which is adapted to register with the opening 9 of the machine head and one end of 95 this section 41 is pivotally supported upon a shaft 43 carried by one of the side walls of the machine head. An auxiliary frame 44 is carried by this main frame having an opening therein adapted to register with the 100 openings 9 and 42. This auxiliary frame 44 is provided with lugs 45 which extend through the marginal recesses formed within the main frame 41 and the pins 46 extend through these lugs 45 for locking the auxiliary frame to the main frame. Secured to the outer face of the main frame by means of the set screws 47 are the leaf springs 48 and the outer free ends of these leaf springs press against the lugs 45 for extending an even 110 pressure upon the opposite ends of the auxiliary frame 44. Surrounding the opening 9 is a guide 49 over which passes the film 2 and carried by this guide 49 is a latch 50 which is adapted to engage the main frame 41 for 115 locking the gate in position. From the construction it is obvious that when the gate is in this locked position the auxiliary frame 41 will press against the film thereby holding the film taut and at the same time permitting the film to be drawn through the gate without injury.

The framing roller 7 is supported by one end of a lever 51 and this lever is pivotally supported as at 52. A leaf spring 53 is carried by this lever and rests against the bottom of the casing 1. A set screw 54 is mounted in the casing 1 and its inner end presses against the projection 55 carried by 120 the lever 51 so that the operator may by 130

turning the set screw 54 adjust the framing roller to a position for properly framing the picture.

From the feeding mechanism herein described it will be seen that the film may be drawn through the machine so that each picture carried by the film will be quickly brought into place within the film gate, momentarily retained within the film gate and quickly drawn from the film gate whereby a clear picture may be projected upon the screen.

Having thus fully described the invention, what I claim as new and desire to secure by Letters Patent, is:—

1. In a moving picture machine comprising a pair of feed sprockets, shafts for supporting said feed sprockets, gears carried by said shafts, a driven pinion meshing with said gears, a beater roller operatively connecting to said pinion and means for momentarily holding one of said feed sprockets against rotation.

2. A moving picture machine comprising feed sprockets and a beater roller, a driving mechanism comprising a main driven shaft, means operatively connecting said main driven shaft with said feed sprockets whereby the feed sprockets will be rotated, means for intermittently retaining one of said feed sprockets against rotation and means for operatively connecting said main driven shaft to said beater roller, substantially as and for the purpose specified.

3. A moving picture machine comprising a film feeding mechanism consisting of feed sprockets and a beater roller, an upper and lower shaft supporting said feed sprockets, gear wheels carried by said shafts, a main shaft, a pinion carried by said main shaft and meshing with said gears, an arm connected to said beater roller, a link connecting said beater arm to said pinion, a disk keyed to said lower shaft, a pin carried by said beater arm and adapted to travel upon the outer periphery of said disk and a flexible connection between said lower shaft and the gear wheel carried thereby substantially as and for the purpose specified.

4. A moving picture machine comprising in combination a film feeding mechanism comprising sprocket wheels, a driving mech-

anism, said driving mechanism comprising a driven shaft, a pinion carried by one end of said driven shaft, gear wheels operatively connected to said sprocket wheels and adapted to mesh with said pinion, a pivotally supported lever, a film beater carried by said lever, a link connecting said lever with said pinion, a shutter shaft, and a worm and gear connection between said shutter shaft and said driven shaft.

5. A moving picture machine comprising in combination a main casing, a film feeding mechanism arranged within said main casing, comprising a pair of sprocket wheels and a beater roller, an auxiliary casing carried by said main casing, shafts extending through said casing and having said sprockets secured thereto, a driven shaft having a portion thereof journaled within said auxiliary casing, a fly wheel pulley secured to said driven shaft and extending exteriorly of said casing, a pinion carried by the inner end of said driven shaft, gear wheels arranged within said auxiliary casing and adapted to mesh with said pinion, one of said gear wheels being keyed to one of said sprockets, an escapement mechanism connecting the other of said gears to one of said sprocket shafts, a shutter shaft journaled within said auxiliary casing and extending at right angles to said driven shaft, and means for operatively connecting said shutter shaft with said driven shaft.

6. In a moving picture machine comprising in combination a film feeding mechanism including a sprocket wheel, a driving mechanism comprising a continuously driven gear wheel, an escapement mechanism arranged for operatively connecting said gear wheel with said sprocket wheel, said escapement mechanism consisting of a disk carried by said sprocket wheel, a leaf spring secured to said disk, a pin carried by said gear wheel and adapted to be engaged by said leaf spring, a notched disk connected to said sprocket wheel, and means operatively connected to said gear wheel for engaging said notched disk, substantially as and for the purpose specified.

In witness whereof I have hereunto set my hand.

CLARK E. CARTER.
